Primary Examiner — Susan Bennett Hattan*Assistant Examiner* — Lauren D McVey(74) *Attorney, Agent, or Firm* — Schultz & Associates, P.C.(57) **CLAIM**

The ornamental design for a rollover simulator, as shown and described.

DESCRIPTION

FIG. 1 is a perspective view of a rollover simulator showing my new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof;

FIG. 8 is a second perspective view thereof;

FIG. 9 is a third perspective view thereof;

FIG. 10 is a fourth perspective view thereof;

FIG. 11 is a fifth perspective view thereof; and,

FIG. 12 is a sixth perspective view thereof.

The broken lines depict environment and form no part of the claimed design.
